BEDRICH MACKU, OF BRÜNN, AUSTRIA-HUNGARY, AND LEONID MANDELSTAM AND NICOLAUS PAPALEXI, OF STRASSBURG, GERMANY.

ARRANGEMENT FOR PRODUCING SLIGHTLY-DAMPED ELECTRICAL OSCILLATIONS.

1,087,126.

Specification of Letters Patent.

Patented Feb. 17, 1914.

Application filed April 26, 1911. Serial No. 623,539.

To all whom it may concern:

Be it known that we, Dr. BEDRICH MACKU, a subject of the Austro-Hungarian Emperor, and residing at Brünn, Austria-Hungary, 5 and Dr. LEONID MANDELSTAM and Dr. NICOLAUS PAPALEXI, subjects of the Russian Emperor, and both residing at Strassburg, Germany, have invented a certain new and useful Improved Arrangement for Producing 10 Slightly-Damped Electrical Oscillations, of which the following is a specification.

This invention relates to an arrangement for producing slightly damped electric oscillations by condenser discharges and the invention 15 enables an oscillation circuit to be so excited by means of a spark gap that when the discharge takes place, the spark is immediately quenched and the circuit oscillates further without a spark gap and is accordingly but slightly damped.

A simple method of carrying out the invention is shown diagrammatically in the figures of the accompanying drawings, in three modifications.

25 Figure 1 represents an arrangement in which the oscillation circuit which contains the slightly damped oscillations is formed by two closed oscillation circuits connected by a common spark gap. Fig. 2 represents 30 an arrangement in which one of the oscillation circuits is open, and Fig. 3 represents an arrangement similar to that shown in Fig. 2 in which the antenna is not charged with the circuit.

35 As may be seen in Fig. 1 two condenser circuits formed of a condenser *c*, the primary coils *t* of a transformer and a self-induction coil *b* are combined with a spark gap *a* common to all. The condensers *c* are 40 charged through charging wires *f*.

Arrangements in which several circuits are also connected with one spark gap are 45 in themselves already known, but in such older arrangements the effect of quenching the spark gap, which is a feature of the present invention does not take place. This action is attained in the present invention by the two circuits connected with the spark gap being of different frequency and the 50 ratio of the capacity to the self-induction in both circuits being made equal or approximately equal. The current intensity in the spark gap during discharging is the sum of the intensities of both circuits. Their 55 amplitude undergoes fluctuations (sur-

ings), the frequency of which is dependent on the tuning and the degree of coupling of the two condenser circuits. By a suitable choice of these values it is possible to effect a quenching of the spark at the point of the 60 minimum amplitude of current resulting from the first surging. By the remaining charges the condenser circuits are now each reversely charged (or charges from the remnant energy still take place) and by 65 equalizing the same the entire system is now caused to oscillate as a single circuit in which both capacities *c* and self-induction coils *t* are connected in series. These oscillations are, however, only slightly damped as 70 the damping influence of the spark is now, entirely eliminated.

An open circuit or, as shown, for instance, in the drawings, an antenna *d* with earth connection *e* may be suitably coupled, for 75 instance, over the secondary coils *t'*, with this exciting circuit. Instead of an inductive coupling a direct connection of the antenna with the oscillation circuit may also be formed. Instead of coupling both separate 80 circuits with the antenna it will also fully suffice to only connect one circuit with them, as when excited the entire energy flows over the transformer coils *t*. If the antenna be caused to act in conjunction with both oscillation circuits *c*, *t*, *b*, as shown in Fig. 1, the coupling must be so arranged that the original oscillations of the separate circuits counteract each other in the antenna. In many 85 cases it is even preferable to couple with 90 each other inductively the two separate circuits *c*, *t*, *b*, in such way that the two transformer coils *t* are brought into close magnetic relation to each other.

One of the two circuits connected with 95 the spark gap may, however, also be formed directly as an open circuit or as antenna. Fig. 2 is a diagram of the simplest form of this modification. *a* is the spark gap, *b* the self-induction coil and *c* the capacity of a 100 closed circuit connected with the spark gap. The second open circuit is here formed by the antenna *d* on the one hand and the earth connection and counterweight *e* on the other hand. *f* are charging wires or conductors 105 coming from the induction coil or transformer. Both circuits are here charged in parallel, and the oscillations are again formed by suitably adapting the constants of the closed circuit to the given proportions 110

of the antenna, which oscillations produce surgings in the spark gap. After the spark is quenched at the first surging, the single circuit composed of *d*, *b*, *c*, and *e* further 5 oscillates with reduced damping.

In the form of construction hereinbefore described the antenna receives the charge directly from the supply current. In order to avoid the well known disadvantages adhering to such connections (the difficulty of making the insulation, the considerable losses owing to small imperfections in insulation and the like), an improvement may be made thereon, as shown in Fig. 3, by inserting a condenser *g* in the antenna and then connecting this condenser by a branch through a large self-induction coil *h* (for instance a choking coil) with the other pole of the spark gap. When charged, the antenna is then itself not charged, but the charge is received on one hand by the condenser *c* of the closed circuit and on the other hand by the condenser *g* over the self-induction coil *h* which offers no appreciable 25 resistance to the charging current. This coil, however, blocks the way to rapid oscillations during the discharge, so that these oscillations again, as before, take place first in the open circuit *d*, *g*, *e*, and also in the 30 closed circuit *b*, *c*, but after the quenching of the spark exclusively in the circuit *d*, *g*, *b*, *c*, *e*. It is a particular advantage of this form of construction that it allows greater 35 quantities of energy to be converted in consequence of the larger capacities available.

We claim:

1. In an arrangement for producing slightly damped electric oscillations, two oscillation circuits, having a portion including a spark gap common to both circuits, and a third oscillation circuit formed by the independent portions of said two first circuits, capacities and self-inductances in said 40

two first circuits suitably proportioned to cause the circuits to oscillate at slightly different oscillation periods, the ratio of capacity to self inductance in each of said two first circuits being equal or approximately 45 equal to cause quenching of the spark by the fluctuations in the oscillation formed in the two first named circuits whereby the energy set in motion continues to oscillate in said third circuit. 50

2. In an arrangement for producing slightly damped electric oscillations, two oscillation circuits, the one circuit being closed, the other being arranged as antenna, having a portion including a spark gap common to both circuits, and a third oscillation circuit formed by the independent portions of said two first circuits, a condenser in said antenna, a coil of high self induction in shunt to said condenser and 55 said spark gap, capacities and self-inductances in said two first circuits suitably proportioned to cause the circuit to oscillate at different oscillation periods, the ratio of capacity to self-inductance in each of said 60 two first circuits being equal or approximately equal to cause quenching of the spark by the fluctuations in the two first named circuits whereby the energy set in motion continues to oscillate in said third circuit. 70
